UNITED STATES PATENT OFFICE

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK

BLANK-HOLDING AND CLUTCH-OPERATING MECHANISM FOR PRESSES

Application filed August 24, 1926. Serial No. 131,221.

This invention relates to a press which is more particularly designed for drawing sheet metal into various shapes and more particularly to the means for holding the sheet of metal while the same is being drawn and the mechanism for controlling the operation of the clutch which connects and disconnects the press with the driving shaft.

One of the objects of this invention is to provide improved means for holding the sheet metal blank while the same is being drawn which means operate quickly and effectively hold the blank with a powerful grip and prevent the same from becoming displaced while being operated upon.

Another object of this invention is to provide improved means for causing the clutch to be started by manual power and to be stopped automatically at the end of each cycle of operations which means are quick in action and operate to start and stop the press promptly.

In the accompanying drawings:—

Figure 1 is a front elevation of a draw press embodying my improvements showing the parts in the position which they occupy when sheet metal blank is being held and drawn.

Figure 2 is a fragmentary elevation of the same viewed from the left hand side.

Figure 3 is a fragmentary elevation of the same viewed from the right hand side and showing a part thereof broken out and shown in section on line 3—3, Figure 1.

Figure 4 is a fragmentary elevation of the press viewed from the left hand side thereof showing the upper holding die and forming tool in the elevated inoperative position.

Figure 5 is a vertical section of the press taken on line 5—5 showing the parts in the position corresponding to Figure 4.

Figure 6 is a horizontal section taken on line 6—6, Figure 1.

Figure 7 is a fragmentary front elevation of the press showing the driving clutch in an open or uncoupled position and parts of the clutch operating mechanism in section.

Figure 8 is a fragmentary vertical section taken on line 8—8, Figure 7.

Figure 9 is a fragmentary vertical section

taken on line 9—9, Figure 7, showing parts of the clutch operating parts in the position which they occupy when the press is at rest.

Figure 10 is a view similar to Figure 7 but showing the position of the parts when the clutch operating mechanism has been tripped by foot pressure and the clutch is closed to couple the driving shaft with the upper holding die and upper forming tool operating mechanism.

Figure 11 is a view similar to Figure 9, but showing the clutch operating mechanism locked for safety when adjusting the dies and tools and getting the press ready.

Figure 12 is a fragmentary perspective view of the clutch operating mechanism.

Similar characters of reference indicate like parts in the several figures of the drawings.

The main frame of this press is of usual construction and comprises a base having a bed or table 20 provided with supporting legs 21, standards 22, 23 rising from said bed, and a head 24 connecting the upper ends of said standards. Upon the bed is arranged the lower holding and drawing die forming part of the means for holding and drawing the sheet metal blank 25. This lower die in the present instance comprises an upright tubular body 26 provided at its lower edge with a flange 27 secured to the top of the bed. Above the lower holding and drawing die is arranged an upper holding die 28 which moves vertically toward and from the upper end of the lower holding die for gripping the sheet metal therebetween, and an upper drawing die or forming tool 29 which is movable vertically through an opening 30 in the upper holding die and adapted to push the adjacent part of the sheet metal blank downwardly into the bore of the lower die the requisite extent to suit the draw desired.

The upper holding die is mounted on the under side of a vertically movable outer slide 95 or cross head 31 which is guided on the inner side of the standards and the upper drawing die or forming tool is mounted on a vertically movable inner slide or cross head 32 which is guided on the outer slide 31.

The numeral 33 represents the main driving shaft of the press which is mounted horizontally and lengthwise in suitable bearings on the lower rear part of the standards and provided with a fly wheel 34 and with tight and loose pulleys 35, 36, adapted to receive a driving belt. Above the die is arranged a crank shaft 37 which is journaled horizontally and lengthwise in suitable bearings in the upper parts of the standards and provided between the same with a main crank 38 which is connected by a connecting rod or pitman 39 with the inner slide 32. At one end the crank shaft is provided with a large gear wheel 40 which meshes with a small gear wheel or pinion 41 on the main driving shaft. This pinion is adapted to be connected with or disconnected from the driving shaft by a clutch which may be of any suitable construction but which preferably is of the friction type and comprises co-operating friction disks or plates 42 connected respectively with a driven member 43 having the form of a brake drum which is connected with the pinion 41 and a driving member having the form of a supporting head 44 splined to the driving shaft, and a shifting sleeve 45 movable lengthwise on the driving shaft and adapted to couple and uncouple the friction plates to transmit motion from the driving shaft to the crank shaft or to interrupt the transmission of such motion.

The means whereby motion is transmitted from the crank shaft to the upper holding die 35 and which contain some of the features of my invention are constructed as follows:

The numerals 46, 46, represent two transverse operating bars arranged above the outer slide and on opposite sides of the pitman and 40 each adjustably connected on its under side with the adjacent part of the outer slide 31 by means of upright adjusting rods 47. Above those operating bars and on opposite sides of the crank shaft arranged front and 45 rear lower rock shafts 48, 49 and above the latter are arranged front and rear upper rock shafts 50, 51, those several rock shafts being arranged horizontally and lengthwise of the press and journaled in suitable bearings on the upper parts of the frame standards, as 50 shown in Figures 1-6.

The front lower rock shaft 48 is provided with two lower rock arms 52 which are connected respectively by links 53 with the front 55 ends of the operating bars 46 and practically form toggles therewith, and the rear lower rock shaft 49 is also provided with two lower rock arms 54 which are connected respectively by links 55 with the rear ends of said operating bars.

The front and rear lower rock shafts are also provided respectively with upper rock arms 56, 57. The front and rear upper rock shafts 50, 51 are provided respectively with lower rock arms 58, 59 and on the left hand

ends those rock shafts are also provided, respectively, with upper rock arms 60, 61 which are arranged outside of the adjacent standard. The lower arm 58 of the upper front rock shaft 50 is connected by a link 62 with the upper rock arm 57 of the lower rear rock shaft 49, and the lower arm 59 of the upper rear rock shaft 51 is connected by a link 63. The links 62 and 63 and the arms associated therewith are arranged in different planes in a direction lengthwise of the rock shafts to permit these links to pass each other, as best shown in Figure 6.

On the outer side of the left hand standard is arranged a vertically movable toggle slide 64 which is guided on an upright bar 65 mounted at its opposite ends on the adjacent standard. At its upper end this toggle slide is connected by front and rear links 66, 67, with the outer rock arms 60, 61 of the upper front and rear rock shafts 50, 51, and the lower end of this slide is connected by a link 68 with an auxiliary crank arm 69 at the left hand end of the crank shaft 37 outside of the adjacent standard, as shown in Figure 1.

The several parts just described are so timed and organized that when the crank shafts start to rotate its outer crank 69 operates to raise the toggle slide 64 and the latter turns the upper rock shafts 50, 51 through the medium of the links 66, 67 and rock arms 60, 61. These shafts in turn rotate the lower rock shafts 48, 49, through the medium of the links 62, 63 and arms 57, 58, 56, 59. Motion is then transmitted from the lower rock shafts 48, 49 by the arms 52, 54 and links 53, 55 to the slide 31 carrying the upper holding die 28 so that the latter is moved downwardly in advance of the upper drawing tool 29 and causes the sheet metal blank to be gripped between the upper and lower holding dies and prevent the same from slipping upon being engaged immediately thereafter by the upper drawing tool 29.

It will be noted that in this holding mechanism the upper holding die is pressed toward the lower holding die by three sets of toggle members, one set of which is interposed between the toggle slide 64 and the upper rock shaft, another set is arranged between the upper and lower rock shaft, and still another set being arranged between the lower rock shaft and the upper holding slide. A very powerful clamping action on the sheet metal is thus obtained which positively prevents displacement of the same and insures proper drawing of the same when engaged by the upper drawing tool. The several sets of toggle members are so arranged that when the upper holding die reaches the limit of the downward motion, the toggle members of the set between the toggle slide and the lower rock shafts will be passing dead centers, as shown in Figures 2 and 3, and the links 62 and 63 will also be passing dead centers rela- 125 130

tively to the corresponding rock arms 58, 59 on the upper rock shafts, as shown in the same figures, thereby providing sufficient dwell in the holding mechanism, and holding the blank with a uniform pressure throughout the drawing operation.

This mechanism for operating the blank holding die is not only very simple and powerful but it is also very light and compact in construction and thus enables the press to be built at less cost and shipped at a lower rate.

Clutch controlling means are provided whereby the clutch hereinbefore mentioned may be operated easily, quickly and reliably so that it can be started promptly by manual power and stopped automatically at the end of each cycle of operations. In its preferred form, this clutch operating mechanism is constructed as follows:

The numeral 70 represents a horizontal shipper rod which is arranged lengthwise below the clutch and guided by a bracket 71 forming part of the main frame. This shipper rod is provided with a forked arm 72 which engages the shifting sleeve 45 of the clutch so as to be compelled to move lengthwise therewith but permits the sleeve to turn independently of said forked arm.

Journalized transversely in the lower part of the bracket 71 is a horizontal rock shaft 73 provided with a rear arm 74 engaging with the shipper rod 70 and front trip arm 75 which is adapted to be operated either manually or automatically. On the inner part of the bracket 71 is pivotally mounted a vertically swinging elbow lever having a lower vertical arm 76 and an upper horizontal arm 77. Between the trip arm 75 and the lower elbow arm 76 is arranged a toggle consisting of two links 78, 79 connected with each other at their opposing ends by a pivot pin 80 while their extremities are pivotally connected respectively, with the trip arm 75 and the lower elbow arm 76. The downward movement of the toggle links 78, 79 when the same are in a straightened, unfolded or dead center position is limited by a stop device consisting preferably of a stop lug 81 arranged on one of these links and engaging with the top of the other link, as shown in Figures 1 and 7.

Pivotally mounted on the upper outer part of the right hand standard is a cam lever of elbow form which engages a trip cam on the crank shaft 37, this cam lever in its preferred form having an upper vertical arm 82 which engages a cam section 83 on the crank shaft and a lower rearwardly projecting arm 84 engaging with a cam section 85 on this shaft, whereby these two cam sections operate like a groove cam for positively rocking the cam lever 82, 84 in opposite directions upon rotating the crank shaft. The lower rearwardly projecting arm 84 of this cam lever is con-

nected by a rod 86 with the upper horizontal arm 77 of the intermediate elbow lever.

The toggle links are folded upwardly by manual power which may be transmitted thereto either by a foot lever or pedal 87 or by a hand lever 88. For this purpose, this hand lever is mounted on a rock shaft 89 journaled on the lower part of the main frame and provided with an inwardly projecting arm 90 which is connected by an upright rod 91 with the toggle link 79, and the pedal 87 is pivoted on the lower part of the frame and connected with the rock shaft 89 by an intermediate rock lever 92 pivoted on the frame and having one of its arms connected by a rod 93 with the pedal while its opposite arm is connected by a rod 94 with the arm 90 on the rock shaft 89. Upon rocking the latter either by foot or hand pressure in the direction for raising the rod 91 the toggle links 78, 79 will be broken or unfolded and cause one of the members with which they are connected to move toward the other.

When the press is at rest the clutch is open or uncoupled and the operating mechanism for the same is in the position shown in Figures 7 and 9. In order to couple the clutch for starting the press the attendant raises the trip rod 91 so as to fold or break the toggle formed by the links 78, 79 during which operation the latter fold upwardly and cause the shipper rod 70 to be moved inwardly so as to couple the clutch, as shown in Figure 10, it being understood that the elbow lever 76, 77, at this time is stationary and forms a fixed anchor or fulcrum for the link 79 and thereby causing an upward movement of these links to positively close the clutch. As the press starts the shipper rod 70 remains in the position in which the clutch is closed or coupled and during the first part of the rotation of the cam 83, 85, with the crank shaft this cam turns the cam elbow lever so that its upper arm 82 moves forwardly and its lower arm 84 moves upwardly, thereby producing an upward pull on the rod 86 and causing the toggle links 78, 79 to again straighten notwithstanding that the arm 75 and the shipper rod connected therewith are stationary at this time, as shown in Figure 1, and the clutch closed.

As the crank shaft approaches the end of the rotation and the press is about to complete a cycle of operations, the cam 83, 85 turns the cam lever so that the arm 82 moves backwardly and the arm 84 moves downwardly, thereby causing a depression of the rod 86 which movement is transmitted by the elbow lever 76, 77 and toggle links 78, 79, now in a straightened condition, to the arms 74, 75 and shipper rod 70 so that the clutch is uncoupled, as shown in Figure 7.

Means are provided for rendering inoperative the mechanism whereby the clutch is coupled so as to prevent operation of the

press when mounting the dies therein, effecting adjustment or repairs or any other service which renders it necessary to operate the machine by hand, stopping and starting the 5 rotation of the crank shaft at will of the operator. The preferred form of locking means for this purpose consists in providing the lower arm 84 of the cam lever with a slot 96 which extends from a point vertically on 10 line with the fulcrum of the cam lever to a point on one side of this line, and a clamping bolt 97 connected with the upper end of the rod 86 and arranged in the slot 96. When the press is in operation the shifting rod is 15 connected with the extremity of the lower arm of the cam lever, as shown in Figure 9, but when it is desired to operate the press by hand, the clamping bolt 97 is shifted to the inner end of the slot 96 so that the shifting 20 rod 86 is in line with the fulcrum of the cam lever, as shown in Figure 11, at which time the turning of the crank shaft is under control of the operator, for setting dies.

When the press completes a cycle of operations it should be stopped as quickly as possible and to do this promptly means are provided which in their preferred form are constructed as follows:—

The numerals 98, 98, represent two brake 30 shoes adapted to engage opposite sides of the brake drum 43 and mounted on the upper arms of brake levers 99 which are pivoted on a lateral extension of the bracket 71. Between these brake levers is arranged an el- 35 bow operating lever which is pivotally mounted on this bracket and has an upwardly projecting arm 100 which connects with the shipper rod 70 and a horizontally extending arm 101 which has its free end 40 arranged between the lower arms of the brake levers and connected therewith by oppositely extending toggle links 102. When the clutch is closed or coupled the operating lever 100, 101, is turned by the shipper rod 45 so as to depress the inner ends of the toggle links 102 to a considerable extent, as shown in Figure 3, whereby the brake levers are turned so as to disengage the brake shoes from the drum 43 and permit the press to run 50 freely. When the shipper rod is moved in the direction for uncoupling or opening the clutch the operating lever 100, 101, is turned in the opposite direction and raises the inner ends of the toggle links 102 so as to spread 55 the lower arms of the brake levers and cause the brake shoes to be pressed against opposite sides of the brake drum and thereby stop the operation of the press quickly.

By means of the herein described im- 60 provements, the press can be operated very rapidly and brought quickly to a stop and the sheet metal blanks are also held very firmly while being drawn, thereby enabling perfect goods to be produced expeditiously 65 and economically.

I claim as my invention:—

1. A press comprising a holding die slide, front and rear rock shafts each having lower rock arms and an upper rock arm, links connecting the lower arms of said lower shafts with said holding die slide, front and rear upper rock shafts arranged above said front and rear lower shafts and each having a lower rock arm and an upper rock arm, a link connecting the lower arm of said front upper rock shaft with the upper arm of said lower rear rock shaft and another link connecting the lower arm of the upper rear rock shaft with the upper arm of the lower front rock shaft, and means for actuating the upper 80 arms of said upper rock shafts.

2. A press comprising a holding die slide, front and rear rock shafts each having lower rock arms and an upper rock arm, links connecting the lower arms of said lower shafts with said holding die slide, front and rear upper rock shafts arranged above said front and rear lower shafts and each having a lower rock arm and an upper rock arm, a link connecting the lower arm of said front upper rock shaft with the upper arm of said lower rear rock shaft and another link connecting the lower arm of the upper rear rock shaft with the upper arm of the lower front rock shaft, a vertically movable toggle slide, 90 and links connecting said toggle slide with the upper rock arms of said upper rock shafts.

3. A press comprising a holding die slide, front and rear rock shafts each having lower rock arms and an upper rock arm, links connecting the lower arms of said lower shafts with said holding die slide, front and rear upper rock shafts arranged above said front and rear lower shafts and each having a lower rock arm and an upper rock arm, a link connecting the lower arm of said front upper rock shaft with the upper arm of said lower rear rock shaft and another link connecting the lower arm of the upper rear rock shaft with the upper arm of the lower front rock shaft, a vertically movable toggle slide, links connecting said toggle slide with the upper rock arms of said upper rock shafts, a crank shaft having a main crank for operating a tool and an auxiliary crank, and a link for connecting said auxiliary crank with said toggle slide.

In testimony whereof I hereby affix my signature.

BROR J. LINDGREN.
